UNITED STATES PATENT OFFICE.

GEORGE HENRY WHEARY, OF RACINE, WISCONSIN.

TRUNK COLLAR AND TRACK.

1,313,769.

Specification of Letters Patent.

Patented Aug. 19, 1919.

Application filed May 3, 1918. Serial No. 232,351.

To all whom it may concern:

Be it known that I, GEORGE HENRY WHEARY, a citizen of the United States, and resident of Racine, in the county of Racine and State of Wisconsin, have invented new and useful Improvements in Trunk Collars and Tracks, of which the following is a description, reference being had to the accompanying drawings, which are a part of this specification.

10 This invention relates to improvements in a trunk collar and track construction more particularly adapted for use in wardrobe trunks.

Trunks of this type are usually divided 15 vertically medially into two sections which are hinged together and are adapted to be swung laterally to open position to permit access thereto. One of the sections is usually divided into drawer and other compartments, and the other section is arranged 20 to hold the apparel which is draped over two point suspension garment hangers, the said hangers being slidably supported on tracks which are mounted on the inner side 25 portions of the wardrobe section. The wardrobe section is usually open at its upper end and is provided with a top cover which is hinged to the rear portion of the wardrobe section or to the front edge portion of the 30 drawer section. As the open end of the wardrobe section materially weakens the said end, the top covers are constructed to overlap the upper edge, or what is termed in the nomenclature of the art, the collar.

35 This collar is usually secured to the inner upper edge portions of the section and projects upwardly from the three sides of the section and is overlapped by the depending flanges of the cover which abut against the 40 upper edges proper of the trunk section when the cover is in closed position. The flanges of the cover are also provided with a depending strip of material which overlaps the upper edges proper of the said section to form a valance. Heretofore the 45 collar of the ordinary trunk has been formed of strips of wood glued and riveted to the upper edge portions of the wardrobe section and the garment hanger tracks have in 50 turn been fastened to a reinforcing band which was fastened to the collar by rivets or screws. This construction is comparatively very expensive to manufacture and does not possess the strength desired. Furthermore, the construction described ma-

and requires considerable space and thereby lessens the capacity of the wardrobe section. Furthermore, in the said construction the garment hangers are formed of 60 wood and have metal hook portions riveted on their outer ends which engage the tracks. Said metal hook portions form sharp shoulders which are liable to injure the garments draped over the hangers unless care is 65 exercised in packing the trunk.

It is one of the objects of the present invention to overcome the before mentioned objectionable features and provide a trunk collar and track construction in which the 70 collar and tracks are formed in a unitary structure of sheet metal.

A further object of the invention is to provide a trunk collar and track construction in which garment hangers of a greater 75 length may be used in a trunk construction of a given size than are ordinarily used, thereby providing greater width of space for draping garments over the hangers mounted on the rails.

A further object of the invention is to provide a trunk collar and track construction for supporting garment hangers in which the use of metal hooks on the ends of the garment hangers is eliminated.

A further object of the invention is to provide a trunk collar and track construction in which the collar and track portion and also the extension tracks are formed of 85 sheet metal.

A further object of the invention is to provide a trunk collar and track construction which serves as a reinforcing means for the open end of the wardrobe section of the trunk.

A further object of the invention is to provide a trunk collar and track construction having sheet metal extension track members which are hinged to the outer ends of the fixed track portions in a manner to 90 form a rigid connection therebetween.

A further object of the invention is to provide a trunk collar and track construction in which the extension tracks thereof may be yieldingly locked in both open and 105 folded position.

A further object of the invention is to provide a trunk collar and track construction in which means are provided for preventing the garment hangers mounted thereon from accidentally slipping off the track portion of said construction.

A further object of the invention is to provide a trunk collar and track construction which is of simple construction, is strong and durable and is well adapted for the purpose described.

With the above and other objects in view the invention consists of the improved trunk collar and track construction and its parts and combinations as set forth in the claims, 10 and all equivalents thereof.

In the accompanying drawing in which the same reference characters indicate the same parts in all of the views:

Figure 1 is a vertical sectional view of 15 the upper portion of the wardrobe section of a wardrobe trunk taken on line 1—1 of Fig. 2;

Fig. 2 is a top view thereof with the top cover removed, the view also indicating 20 by dotted lines the extension tracks in open position;

Fig. 3 is a vertical sectional view of the 25 upper portion of the wardrobe section taken on line 3—3 of Fig. 1, the extension track member being shown in open position;

Fig. 4 is a sectional detail view taken on line 4—4 of Fig. 2; and

Fig. 5 is a transverse sectional detail view 30 of a modified form of collar and track.

Referring to the drawing the numeral 8 indicates the wardrobe section of a wardrobe trunk which is arranged to be swung horizontally to open position. The upper end of the wardrobe section is open as indicated by the numeral 9 and is covered by 35 a top cover 10 which is preferably hinged to the upper forward edge of the other section (not shown) and swings over and closes the wardrobe section when said section is in closed position.

The top cover is provided with depending flanged portions 11, the lower edge portions of which abut against and rest upon the upper edge portions of the wardrobe 45 section. The depending flanges of the top cover are provided with a strip of material 12 along its lower edge portion which overlaps the upper edge portion of the wardrobe section when the said section is in 50 closed position and the cover is swung thereover.

The trunk collar and track 13 is formed of sheet metal and is connected to the inner edge portion of the upper open end of the 55 wardrobe section of the trunk by rivets or screws 14 and projects upwardly therefrom a sufficient distance to form comparatively a wide collar which is overlapped by the depending flanges of the top cover when 60 the cover is in a closed position. The collar and track is of approximately U-shape in plan view and of angular shape in cross section, and comprises side members 15 and a rear member 16 which are provided with 65 forwardly bent tongues 17 and 18. These

tongues overlap the rear end portions of the side members 15 and are riveted thereto to rigidly connect the parts together. The upper portion 16' of the rear member 16 medially of its height is offset inwardly at 70 right angles to provide a sufficient clearance for the depending rear flange of the top cover, and the upper portions 15' of the side members 15 are also offset inwardly at right angles to provide clearance for the 75 depending side flanges of the top cover. The side members 15 are also provided with inwardly bent and folded portions 19 to form parallel horizontally extending tracks for supporting the outer ends of the garment 80 hangers 20 slidably mounted thereon. These hangers are of a length slightly shorter than the distance apart of the upper portions 15' of the side members 15 to permit the free 85 sliding movement of the hangers on the tracks. It will be noted that the use of metal hooks on the outer ends of the garment hangers is eliminated thus providing greater length of space for draping garments thereon and also eliminating the possibility of injury to garments draped on 90 the hangers.

In the event that it is desired to only use the device as a track and reinforcing means it may be mounted within a trunk 95 part in a position so that its collar portion will not project above the opening of the trunk, and in some cases the rear member of the device may be eliminated when the reinforcement is not necessary.

The forward ends of the side members 15 are bent and shaped to have extension tracks 21 hinged thereto, as indicated by the numeral 17', and arranged to permit said extension tracks to swing from a folded position shown in Fig. 1 to an extended or open position shown in Fig. 3 and in dotted lines in Fig. 2. The extension tracks are of L-shape in cross section to support the garment hangers and prevent endwise movement thereof and are provided with stop flanges 22 to prevent the accidental disengagement of the hangers with the tracks. Said extension tracks at their rear ends have short projecting portions 23 which extend between the folded portions of the fixed tracks of the side members and the extension tracks are braced by said folded portions. The projecting portions 23 have upturned stop fingers 24 which bear against the outer side portions of the collars 15' and limit the outward swing of the extension track members to aligned positions with the fixed tracks, and the inward swing of said extension tracks is limited by the engagement 115 of the inner edge portions of said tracks against the shoulders 25 of the side members 15.

The projecting portions 23 are also provided with downwardly embossed project- 120

ing knobs 25 which snap into recesses or indentations 26 to yieldingly lock the extension tracks in either open or folded positions.

5 The top cover is shown as provided with a pad 27 into which garments draped on the hangers embed and are retained in position without injury.

In the modified form shown in Fig. 5 the 10 inner edges 19' (only one being shown) of the folded portions 19 are bent upwardly and the lower edge portions of the upper parts of the garment hangers are notched as at 28 to prevent the hangers from accidentally 15 disengaging the tracks by moving them in an oblique direction with relation to the tracks.

From the foregoing description it will be 20 seen that combined collar and track is formed of sheet metal, is of light weight and is strong and durable, and that the use 25 of hooks on the ends of the hangers is eliminated, and the structure is well adapted for the purpose described.

25 What I claim as my invention is:

1. The combination of a trunk, of a collar and track therefor, comprising strips of material shaped to conform to the contour of a trunk portion and having opposite inwardly projecting portions forming a track for supporting garment hangers and upwardly extending portions forming a collar.

2. The combination of a trunk, of a track therefor, consisting of sheet metal side members connected to portions of the trunk and having inwardly projecting portions forming garment hanger supporting means and upwardly extending portions for limiting 40 endwise movement of hangers supported on the inwardly projecting portions.

3. The combination with the wardrobe section of a trunk, of a track therefor, consisting of sheet metal side members connected to the side portions of the trunk section and having inwardly projecting track portions for supporting garment hangers and upwardly extending portions, said inwardly projecting portions extending medially of the height of said side members.

4. The combination with the wardrobe section of a trunk, of a track therefor, consisting of sheet metal side members connected to the side portions of the trunk section and having inwardly projecting folded track portions for supporting garment hangers slidably thereon.

5. The combination with the wardrobe section of a trunk, of a track and collar therefor, consisting of a strip of sheet metal shaped to conform to the contour of an open portion of the trunk and fastened to the inner surfaces of the walls of said trunk portion and projecting outwardly therefrom beyond the open edges of said trunk portion

to form a collar having opposite side portions and a rear portion, the side portions having medial inwardly projecting portions forming tracks for supporting garment hangers slidably thereon.

70

6. The combination with the wardrobe section of a trunk, of a collar and track therefor, comprising a U-shaped strip of metal fastened to the inner surfaces of the walls of an open portion of the trunk and projecting inwardly and outwardly therefrom to form a collar offset inwardly and having opposite side portions and a rear portion, the said side portions having medial inwardly projecting folded portions forming tracks for supporting garment hangers slidably thereon.

75

7. The combination with the wardrobe section of a trunk, of a collar and track therefor, comprising a U-shaped strip of metal fastened to the inner surfaces of the walls of an open portion of the trunk and offset inwardly and projecting outwardly therefrom to form a collar, the said side portions having medial inwardly projecting folded portions forming tracks for supporting garment hangers thereon.

80

8. The combination with the wardrobe section of a trunk, of a collar and track therefor, comprising strips of metal joined together into U-shape and fastened to the inner surfaces of the walls of an open portion of the trunk and having opposite side portions and a rear portion, said portions being offset inwardly and projecting outwardly therefrom to form a collar, the said side portions along the line of the offset being folded inwardly to form tracks for supporting garment hangers slidably thereon, and extension tracks hinged to the outer 100 end parts of said side portions and movable from folded positions to positions in alignment with the first mentioned tracks.

95

9. The combination with the wardrobe section of a trunk, of a collar and track therefor, comprising a rear member and side members connected together to form a U-shaped structure which is mounted within the open end of said wardrobe section, the upper portion of the rear member medially 110 of its height being offset inwardly to form a collar part, the upper portions of said side members medially of their height being offset inwardly to form collar part and also being folded to form tracks for slidably supporting garment hangers thereon, and extension tracks hinged to the outer ends of the side members and movable from a folded position to positions in alignment 115 with the first mentioned tracks.

120

10. The combination with the wardrobe section of a trunk, of a collar and track therefor, comprising a rear member and side members connected together to form a U-shaped structure which is mounted within 125

130

- the open end of said wardrobe section, the upper portion of the rear member medially of its height being offset inwardly to form a collar part, the upper portions of said side members medially of their height being offset inwardly to form collar part and also being folded to form tracks for slidably supporting garment hangers thereon, and extension tracks hinged to the outer ends of the side members and movable from a folded position to positions in alinement with the first mentioned tracks and having portions which extend between the folded parts of said first mentioned tracks.
11. The combination with the wardrobe section of a trunk, of a collar and track therefor, comprising a rear member and side members connected together to form a U-shaped structure which is mounted within the open end of said wardrobe section, the upper portion of the rear member medially of its height being offset inwardly to form a collar part, the upper portions of said side member medially of their height being offset inwardly to form a collar part and also being folded to form tracks for slidably supporting garment hangers thereon, and extension tracks hinged to the outer ends of the side members and movable from a folded position to positions in alinement with the first mentioned tracks, and means yieldingly locking the extension tracks in open and folded positions.
12. A collar and track, consisting of a U-shaped member having inwardly offset and upwardly extending collar portions, the opposite side parts of said member medially of their height being folded inwardly to form track portions.
13. A collar and track, consisting of a U-shaped member having inwardly offset and upwardly extending collar portions, the opposite side parts of said member medially of their height being folded inwardly to form track portions, and extension track members hinged to the outer ends of the track portions and movable from a folded position to positions in alinement with the track portions.
14. A collar and track, consisting of a U-shaped member having inwardly offset and upwardly extending collar portions, the opposite side parts of said member medially of their height being folded inwardly to form track portions, extension track members hinged to the outer ends of the track portions and movable from a folded position to positions in alinement with the track portions, and means yieldingly locking the extension tracks in open and folded positions.
15. A collar and track, consisting of a U-shaped member having inwardly offset and upwardly extending collar portions, the opposite side parts of said member medially of their height being folded inwardly and upwardly to form track portions.
16. The combination with a suspension garment hanger having a notched edge portion, of a collar and track therefor, consisting of a side member having an inwardly offset and upwardly extending collar portion, the said side member medially of its height being folded inwardly and upwardly to form a track portion, the upturned part of which enters the notch of the garment hanger.

In testimony whereof I affix my signature.
GEORGE HENRY WHEARY.
